CLAIM

I claim the ornamental design for a floating table, as shown and described.

DESCRIPTION

FIG. 1 is a perspective view of a floating table, showing a first embodiment of the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a perspective view of a second embodiment of the invention;

FIG. 9 is a top plan view of FIG. 8; and,

FIG. 10 is a bottom plan view of FIG. 8.

The broken lines showing water in FIGS. 1 and 8 are included for the purpose of illustrating environmental matter while the invention is in use, and form no part of the claimed design. The left, right, front, and rear elevational views of the second embodiment are understood to be substantially identical with those views of the first embodiment.
